CLAIM

We claim the ornamental design for blower housing, as shown and described.

DESCRIPTION

FIG. 1 is a perspective view of an embodiment of a blower housing;

FIG. 2 is a top view of the blower housing of FIG. 1;

FIG. 3 is a bottom view of the blower housing of FIG. 1;

FIG. 4 is a right side view of the blower housing of FIG. 1;

FIG. 5 is a left side view of the blower housing of FIG. 1;

FIG. 6 is a front view of the blower housing of FIG. 1;

FIG. 7 is a back view of the blower housing of FIG. 1;

FIG. 8 is a perspective view of another embodiment of a blower housing;

FIG. 9 is a top view of the blower housing of FIG. 8;

FIG. 10 is a bottom view of the blower housing of FIG. 8;

FIG. 11 is a right side view of the blower housing of FIG. 8;

FIG. 12 is a left side view of the blower housing of FIG. 8;

FIG. 13 is a front view of the blower housing of FIG. 8; and, FIG. 14 is a back view of the blower housing of FIG. 8.

The ornamental design which is claimed is shown in solid lines in the drawings. The broken lines in the drawing are for illustrative purposes only and form no part of the claimed design. For example, broken lines formed by equal length dashes show unclaimed portions of the design. Also, for example, broken lines formed of unequal length dashes (e.g., dash-dot) show boundaries between claimed and unclaimed portions of the design.
